UNITED STATES PATENT OFFICE.

PAUL CONLON EGAN, OF MOUNT VERNON, NEW YORK.

LIGHTING FIXTURE.

Application filed February 26, 1923. Serial No. 621,161.

To all whom it may concern:

Be it known that I, PAUL C. EGAN, a citizen of the United States, residing at Mount Vernon, in the county of Westchester and State of New York, have invented an Improvement in Lighting Fixtures, of which the following is a specification.

My invention relates generally to electric light fixtures and more particularly to means for supporting the globes or other forms of shades made use of in such fixtures.

The object of my invention is to provide a screwless holder with means for supporting the shade or globe in such manner that it is impossible for it to fall accidentally, but which may be easily placed in position, or unlocked and removed, when desired, for cleaning or other purposes.

In carrying out my invention I make use of a screwless holder or socket cover in which are hung a plurality of globe supporting legs, in such manner that before the globe is placed in position they are uniformly balanced in a position to allow their lower ends to enter the opening in the shade or bowl when the neck of the bowl is inserted within the base of the holder, and by the employment of a clamping ring surrounding the holder above its base and acting upon the projecting upper ends of such legs, said lower ends of said supporting legs are swung outward and into contact with the interior surface of the bowl below its rim and securely held in such position when the said clamping ring is pushed down upon the upper surface of the base or lower part of said holder.

The details of the invention are herein-after particularly described.

40 In the accompanying drawing:

Figure 1 is an elevation of a lighting fixture embodying my invention, partly in section and with the holder or socket cover, clamping ring and bowl broken away, showing the parts assembled but in unlocked position.

Fig. 2 is a similar view showing the parts in locked position, and

Fig. 3 is a top view of the holder, the globe supporting legs and clamping ring being removed.

Referring to the drawing 10 indicates the holder or socket cover, provided with an integral enlarged bottom 11, in the top of which a plurality of spaced slots 12, are

made, preferably three, as shown most clearly in Fig. 3.

13 denotes the globe supporting legs, which are preferably cut out of a flat piece of metal and bent up to the shape shown in Figs. 1 and 2. These legs are at a predetermined point below their upper ends offset as at 14, below which they are of a thickness and width slightly smaller than the slots 12 in the holder 10, through which they are passed, the shoulder formed by the offset 14, seating upon the top of the holder in such manner as to permit a forward and backward movement of the legs. Three of these legs 13, are preferably employed, and when they are in position in the holder 10, they are uniformly balanced, so that before the parts are locked together they assume the position shown in Fig. 1, in which position it will be readily seen, that when the shade or globe 15, is placed into the bottom 11 of the holder, these legs will pass through the opening in the globe, their lower ends clearing the rim of the bowl, but to avoid any possibility of the ends of the legs catching upon the rim of the bowl, I preferably bend the lower end of each leg downwardly and slightly inwardly, forming a guide 16 at this end of each of the legs 13.

17 denotes a clamping ring fitting over the socket cover 19, and provided at its bottom with a concave skirt 18. This ring 17 is movable vertically upon the socket cover, and acts upon the upper ends of the globe supporting legs 13 to swing their lower ends outward and into contact with the interior surface of the globe 15, below its neck or rim.

In assembling the parts, the globe, bowl or shade 15, is placed within the bottom 11 of the holder 10, as shown in Fig. 1 in doing which, the lower ends of the legs 13 drop into the bowl as before described. The clamping ring 17 is then pushed downward over the upper ends of the legs 13, these ends of the legs first passing under the concave skirt 18 of the ring 17 by which they are guided into the vertical portion of the ring which in turn presses them into a vertical position against the socket cover, at the same time swinging the lower ends of the legs outwardly into contact with the inner surface of the globe 15 as shown in Fig. 2. When the clamping ring 17 is fully depressed as shown in Fig. 2, the globe sup-

porting legs 13, are securely held in the position shown in such figure and when the holder is suspended by a chain or other device connected to the ring 19, the globe and holder cannot accidentally become separated, it being necessary to raise the clamping ring in order to release the bowl.

While the skirt 18, of the ring 17 extends sufficiently over the upper ends of the legs 13, in assembling the parts to pass over such ends, I prefer to bend the upper end of each leg inward as at 20, to prevent any possibility of any one of the legs passing outside said skirt when the clamping ring is lowered.

In order to render the device "fool-proof," I prefer to provide means for preventing the lifting of the binding ring 17 through careless handling, after the parts have been assembled, and for this purpose I cut out the upper inturned rim of the clamping ring 17, at two opposite points, and turn up the cut out portions at right angles at one end of each opening forming stops 21, the openings or slots 22, thus formed in the rim of the ring 17, being passed over projections or lugs 23, on the socket cover 10, when the ring 17 is placed in position.

These projections or lugs 23 may be formed on the socket cover 10, by cutting out tongues and bending them outward at right angles as shown in Figs. 1 and 2, or they may be simply pressed out in forming the shell.

When the clamping ring 17, is pushed down into the position shown in Fig. 2, the lugs 23, pass through the openings or slots 22, when by giving the ring 17, a partial rotation its rim will pass under the lugs 23, which effectually prevents the ring 17 being raised unintentionally or by careless handling.

The ring may be given a half rotation which will bring the stops 21, against the lugs 23, and prevent further rotation of the ring in that direction, preventing its being

lifted until it has been rotated in the opposite direction sufficiently far to bring the openings or slots 22, in alignment with the lugs 23.

It will be seen that my invention provides a simple and efficient screwless type of support for a bowl, globe or shade in lighting fixtures, and by which the assembling or un-assembling of the parts is greatly facilitated; furthermore the lower ends of the globe supporting legs have sufficient spring to give a resilient bearing upon the globe, thus being adapted to act upon globes of various thicknesses, without liability of injury to the glassware.

What I claim as my invention, and desire to secure by Letters Patent is:

1. A device of the character described, comprising a socket cover provided with a plurality of spaced slots, globe supporting legs hung in said slots, and a clamping ring acting upon the upper ends of said legs to swing their lower ends outwardly.

2. A device of the character described, comprising a socket cover provided with a plurality of spaced slots, globe supporting legs hung in said slots, a clamping ring slideable upon said socket cover and by means of which the lower ends of said legs may be swung outwardly, and means for preventing the accidental vertical movement of said clamping ring when the parts are assembled for use.

3. In a lighting fixture, the combination of a shell adapted to cover a lamp socket, and provided with a plurality of spaced slots, globe supporting legs hung in said slots, a bowl or shade having its neck within the lower part of said shell, and a clamping ring acting upon the upper part of the said legs to swing their lower ends into contact with the inner surface of the bowl.

Signed by me this 16th day of February, 1923.

PAUL CONLON EGAN.
